UNITED STATES PATENT OFFICE.

JENO VON MARSOVSZKY, OF BUDAPEST, HUNGARY.

TREAD-OPERATED CIRCUIT CLOSER.

Application filed November 21, 1924, Serial No. 751,295, and in Hungary January 31, 1924.

There are known signalling devices operated by foot pressure which on the one hand give a signal of short duration only, and on the other hand are considerably complicated and therefore expensive. The signalling device forming the subject of the present application gives, on the contrary, upon a single pressure of the foot, a continuous bell alarm in another place and is in consequence of its simple construction very cheap to produce.

In the drawing is shown an example of the subject of the invention, in which:

Figure 1 is a side view of the signalling device, Fig. 2 is similarly a side view somewhat enlarged and in which one side of the casing is removed, and Fig. 3 shows schematically the general arrangement of the signalling device and connections.

One part of the signalling apparatus, which is adapted to be operated by the foot pressure, is placed upon the floor in the locality where it is anticipated that an emergency will arise. This part of the apparatus is enclosed within a casing *a*. Inside this casing is arranged a switch *d* provided with contacts *b*, *c* and having fixed to one end of a switch arm *f* a weight *h* suspended from a cord *g*. The end of the switch arm *f* is provided with a downwardly projecting hook *p*. Upon a pin *i* also within the casing is rotatably mounted a lever comprising two arms *j*, *k*. The ends of the lever arms are bent to hook-shape, whereby the hoop *p* of the switch arm *f*, can be engaged with the hooked end of the lever arm *j* and the hook-shaped end of the arm *k* lies within the fork *n* of a rod *m* which passes out through an opening *l* situated in the front wall of the casing *a* and is under the influence of a spring *q*. The electric leads passing from the switch *d* lead into a neighbouring room, or into the street or other desired place where assistance may be waiting, and at this place an electric alarm bell *o* is connected in the circuit.

The device works as follows:

On open switch, the hooked end *p* of switch arm *f* engages the hooked end of the arm *j*, so that the contacts *b*, *c* of the switch *d* do not rest in contact and the circuit of the bell *o* is broken. If now a mishap occurred to a person in the locality equipped

with the signal device, the rod *m* situated adjacent the floor must be trodden upon or an object let fall thereon, which object may be the body of the person in difficulty. The rod is thus set in motion, and the device quickly operates, whereupon the alarm apparatus will sound continuously until it is switched off. Upon the downward pressure of the rod *m* the lever *k*, *j* turns on the pin *i* in the direction of the arrow Fig. 2 whereby the switch arm *f* becomes free and is pressed downwardly in the direction of the other arrow by the weight *h*, whereupon the rod *m* is quickly returned to its original position under the operation of spring *q*. The contacts *b*, *c* now rest upon one another, the electric circuit is completed and the bell *o* gives a continuous alarm signal. When the danger is over the end of the switch arm *f* is drawn up by pulling down the cord *g*, whereupon the hook *p* comes adjacent the hook of the arm *j* and engages therewith. A switch is once more in open position.

Instead of a weight *h* hung by a cord *g* a spring may also be provided which tends to press the arm *f* downwardly and which operates when the end of the arm *f* releases from the arm *j*.

The main advantage of the apparatus is that it may be operated without being noticed by an assailant or other person who might otherwise prevent a signal being given.

I claim—

1. Tread operated switch for an electric alarm circuit, comprising a tread operated rod, a pivotal switch arm, a two armed lever one arm of which engages the operating rod and the other arm having a releasable catch engagement with the switch arm when the latter is in open position, switch contacts carried by the switch arm, co-operating contacts positioned beneath said switch arm, and a weight carried by the switch arm so that when the latter falls on being released by the operation of the rod the two sets of contacts are securely electrically closed, for the purpose set forth.

2. Tread operated switch for an electric alarm circuit, comprising a casing, a tread operated rod having a forked end passing into and resiliently supported in said casing, a switch arm pivotally mounted in

2
said casing, a two armed lever pivotally mounted in said casing and having releasable catch engagement with the switch arm when the latter is in open position, switch contacts carried by the switch arm, co-operating contacts positioned beneath said switch arm, a weight carried by the switch arm so that when the latter is released by the operation of the rod the two sets of contacts will be forced into secure electrical engagement, and resetting means attached to the switch arm and passing through the casing, for the purpose set forth. 10
JENO VON MARSOVSZKY.
